UNITED STATES PATENT OFFICE.

JAMES F. STRONG, OF DETROIT, MICHIGAN.

WIRE FENCE.

SPECIFICATION forming part of Letters Patent No. 258,501, dated May 23, 1882.

Application filed January 26, 1882. (No model.)

To all whom it may concern:

Be it known that I, JAMES F. STRONG, of Detroit, in the county of Wayne and State of Michigan, have invented new and useful Improvements in Wire Fences; and I do hereby declare that the following is a full, clear, and exact description thereof, reference being had to the accompanying drawings, which form a part of this specification.

10 The nature of this invention relates to certain new and useful improvements in the construction of wirefences, adapted to be built up in sections and rolled up for convenience in transportation; and the invention consists in the method of packing the fence for transportation, as more fully hereinafter described and claimed.

15 Figure 1 is an elevation of a section of my improved fence. Fig. 2 is a perspective showing the section rolled up.

20 In the accompanying drawings, which form a part of this specification, A A represent the two end posts of a section of my improved fence, and to these posts I rigidly secure the 25 ends of the wires B, which are of equal length. If desired, the wire used in the construction of the fence may be of barbed wire.

25 C represents stretcher-bars designed to retain the posts at the proper distances apart and 30 to stretch the wire. These bars are secured to the posts A by suitable pins and holes, or in any other convenient manner.

35 A fence of this description may be constructed in sections and rolled up in a compact mass, as shown in Fig. 2, for the purpose of carrying or transportation.

In setting up this fence the two adjoining posts of the sections should be securely bound together, and the fence set up in a zigzag line, or in the manner of an ordinary rail fence; or, 40 if preferred, it may be set in a straight line and secured to its proper position by means of stakes applied in any of the well-known ways.

A fence constructed as herein described will be easy to manufacture, while it can readily be 45 taken down or adjusted to any desired position.

I am aware that it is not new to construct portable fences in panels partly of wood and partly of wire, and I do not claim such construction, my invention being confined to a 50 panel having wires permanently secured to posts and adapted to be stretched tight by wooden rails detachably secured to the posts, and the posts and wires to be rolled around the rails for transportation.

55

What I claim is—

The method herein described of packing a fence for transportation, consisting in first separating the rails from the posts, leaving the wires attached, placing the rails and one 60 of the posts together, and winding the wires around said rails and posts, thus bringing both of the posts and both of the rails in close proximity and securely holding the whole together, substantially as described.

JAMES F. STRONG.
